UNITED STATES PATENT OFFICE

JOHN T. HARNETT, OF PHILADELPHIA, PENNSYLVANIA.

COMBINATION BATH TRAP, WASTE, AND OVERFLOW.

1,070,372.

Specification of Letters Patent. Patented Aug. 12, 1913.

Application filed December 16, 1911. Serial No. 666,165.

To all whom it may concern:

Be it known that I, JOHN T. HARNETT, a citizen of the United States, residing at Philadelphia, in the county of Philadelphia and State of Pennsylvania, have invented 5 new and useful Improvements in Combination Bath Traps, Wastes, and Overflows, of which the following is a specification.

My invention relates to new and useful 10 improvements in combination bath trap, waste and over-flow, and has for its object to provide an exceedingly simple and effective device of this character which will be strong in construction, inexpensive in the 15 cost of manufacture, easily mounted in position and quickly taken apart when necessary.

Another object of the invention is to produce a trap, waste and over-flow for bath 20 tubs combined into one fixture, which will be mounted beneath the tub but above the floor, thus doing away with a number of "wipe" joints.

A further object of the invention is to provide 25 a single trap for the waste and over-flow which may be readily and quickly reached should it become clogged.

With these ends in view, this invention consists in the details of construction and 30 combination of elements hereinafter set forth and then specifically designated by the claims.

In order that those skilled in the art to which this invention appertains may understand 35 how to make and use the same, I will describe its construction in detail, referring by numeral to the accompanying drawing forming a part of this specification, in which—

40 Figure 1, is a side elevation of the bath trap, waste and over-flow made in accordance with my improvement. Fig. 2, a plan view thereof, and Fig. 3, a vertical sectional view thereof.

45 In carrying out my invention as here embodied, 2 represents a casing preferably cylindrical in shape, open at the upper end and provided with internal threads 3, into which is threaded a cover 4, having an externally 50 threaded integral collar 5, provided with an opening 6 passing entirely through the cover

4. Upon the collar 5 is threaded a nut 7 carrying a resilient ring 8, said resilient ring expanding as the nut 7 is threaded upon the 55 collar 5 causing said resilient ring to firmly grip the over-flow pipe 9. The upper end of

the over-flow pipe 9, is securely mounted in the bath tub and carries a screen or shield 10 while the lower end thereof enters the casing 2 through the opening 6 in the cover 4. 60

11 denotes the waste pipe having an external flange 12, which under-lies the bottom of the bath tub and said pipe is provided with internal threads 13 into which is threaded the cap 14, provided with external threads 15 and carrying an external flange 16 adapted to over-lie the bottom of the bath tub, it being understood that the cap is open to permit the passage of the waste water. The waste pipe 11 is joined to one end of the 70 inlet pipe 17 and held in place by a nut 18, the opposite end of said inlet pipe 17 being mounted in the casing 2, near the bottom thereof, thus making a connection between said casing and the waste pipe 11. Leading 75 from the casing 2, in proximity to the bottom, is an outlet pipe 19, the outer end thereof being joined to the elbow or trap pipe 20 by the nut 21.

In practice the fixture being mounted 80 above the floor, it may be easily installed and without the use of "wipe" joints and when it becomes clogged, the casing may be opened to remove the foreign matter by backing off the nut 7 and unthreading the 85 cover 4 from the casing 2.

Of course, I do not wish to be limited to the exact details of construction here shown as these may be varied within the limits of the appended claims without departing from 90 the spirit of my invention.

Having thus fully described my invention, what I claim as new and useful, is—

1. In a device of the character stated, a casing having a closed bottom and an open 95 top, a cap threaded into the top of the casing for closing the same, an inlet pipe leading from the bottom of the bath tub to one side of the casing adjacent its lower end, an outlet pipe leading from the opposite side of the 100 casing in alignment with the inlet pipe, a trap connected with the outlet pipe outside of the casing, an overflow pipe leading from the upper portion of the bath tub, and projecting through the cap, and means for detachably securing said over-flow pipe in the cap. 105

2. In a combination trap, waste and over-flow, a casing open at the top and provided with internal threads, a cover having an integral externally threaded collar and provided with an opening, an over-flow pipe 110

leading from the bath tub, and mounted in the opening in the cover, a nut surrounding said pipe, and threaded upon the collar, an inlet pipe carried by the casing, a waste pipe having a flange adapted to overlie the bottom of the tub, a nut for joining the waste pipe to the inlet pipe, an outlet pipe leading from the casing, in alignment with the inlet pipe, and a trap connected with the outlet pipe outside of the casing, whereby the in-

terior of the casing is left unobstructed for the removal of foreign matter.

In testimony whereof, I have hereunto affixed my signature in the presence of two subscribing witnesses.

JOHN T. HARNETT.
